(57) **CLAIM**

We claim the ornamental design for a two sided crown moulding, as shown and described.

DESCRIPTION

FIG. 1 is an end elevation view of a two sided crown moulding;

FIG. 2 is a fragmentary front side isometric view of the two sided crown moulding of FIG. 1 with the back side view being similar to the front;

FIG. 3 is an end elevation view of a second embodiment of a two sided crown moulding;

FIG. 4 is a fragmentary front side isometric view of the two sided crown moulding of FIG. 3 with the back side view being a mirror image thereof;

FIG. 5 is an end elevation view of a third embodiment of a two sided crown moulding;

FIG. 6 is a fragmentary front side isometric view of the two sided crown moulding of FIG. 5 with the back side view being similar to the front;

FIG. 7 is an end elevation view of a fourth embodiment of a two sided crown moulding;

FIG. 8 is a fragmentary front side isometric view of the two sided crown moulding of FIG. 7 with the back side view being similar to the front;

FIG. 9 is an end elevation view of a fifth embodiment of a two sided crown moulding;

FIG. 10 is a fragmentary front side isometric view of the two sided crown moulding of FIG. 9 with the back side view being similar to the front;

FIG. 11 is an end elevation view of a sixth embodiment of a two sided crown moulding;

FIG. 12 is a fragmentary front side isometric view of the two sided crown moulding of FIG. 11 with the back side view being similar to the front;

FIG. 13 is an end elevation view of a seventh embodiment of a two sided crown moulding;

FIG. 14 is a fragmentary front side isometric view of the two sided crown moulding of FIG. 13 with the back side view being similar to the front;

FIG. 15 is an end elevation view of an eighth embodiment of a two sided crown moulding;

FIG. 16 is a fragmentary front side isometric view of the two sided crown moulding of FIG. 15 with the back side view being similar to the front;

FIG. 17 is an end elevation view of a ninth embodiment of a two sided crown moulding;

FIG. 18 is a fragmentary front side isometric view of the two sided crown moulding of FIG. 17 with the back side view being similar to the front;

FIG. 19 is an end elevation view of a tenth embodiment of a two sided crown moulding;
FIG. 20 is a fragmentary front side isometric view of the two sided crown moulding of FIG. 19 with the back side view being similar to the front;
FIG. 21 is an end elevation view of an eleventh embodiment of a two sided crown moulding;
FIG. 22 is a fragmentary front side isometric view of the two sided crown moulding of FIG. 21 with the back side view being similar to the front;
FIG. 23 is an end elevation view of a twelfth embodiment of a two sided crown moulding also shown in FIG. 24; and,

FIG. 24 is a fragmentary front side isometric view of the two sided crown moulding of FIG. 23 with the back side view being similar to the front.

The separation lines are used to indicate that the precise length of the two sided crown moulding is not claimed, but rather the length of the two sided crown moulding is indeterminate. The separation lines form no part of the claimed design.
